United States Patent

Des. 235,850

Patented July 15, 1975

235,850

SPARK PLUG WIRE POSITIONER

Mariano P. Diforte, Jr., Baltimore, Md., assignor to
Bat-Weight, Inc., Baltimore, Md.

Filed Sept. 17, 1973, Ser. No. 397,714

Term of patent 14 years

Int. Cl. D8—08

U.S. Cl. D8—231

Fig. 1

Fig. 2

Fig. 3

Fig. 4

FIG. 1 is a plan view of a spark plug wire positioner showing my new design;

FIG. 2 is a right side elevational view thereof;

FIG. 3 is an end elevational view taken from one end thereof; and

FIG. 4 is an end elevational view thereof taken from the opposite end thereof shown in FIG. 3.

The left side elevational view is a mirror image of FIG. 2.

I claim:

The ornamental design for a spark plug wire positioner, as shown and described.
